(57) **CLAIM**

The ornamental design for an electrical vehicle charger, as shown and described.

DESCRIPTION

FIG. 1 is a top perspective view of an electrical vehicle charger showing the new design;

FIG. 2 is a bottom perspective view thereof;

FIG. 3 is top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.

The broken lines depict the portions of the cable and the status light which form no part of the claimed design.
